UNITED STATES PATENT OFFICE.

WILLIAM H. STRAUSER, OF FAIRMONT, WEST VIRGINIA.

MULTIPLE-CHARACTER STENCIL.

1,380,850.

Specification of Letters Patent. Patented June 7, 1921.

Application filed April 11, 1921. Serial No. 460,340.

To all whom it may concern:

Be it known that I, WILLIAM H. STRAUSER, a citizen of the United States of America, and resident of Fairmont, county of Marion, and State of West Virginia, have invented certain new and useful Improvements in Multiple-Character Stencils, of which the following is a specification.

This invention relates broadly to stencils of multiple character type and it has for its primary object to provide an improved hand tool whereby any of a series of characters may be readily applied to or impressed in articles of wood, metal, or the like.

15 A further object is to provide a steel stencil embodying a rotary disk and an impact shank or head which are so associated that the force of the blows applied to the latter is distributed over a relatively 20 large area of the peripheral surface of the disk instead of being received by a pivot or axle in the manner usual to such devices.

A still further object is to provide a device of the character mentioned embodying 25 means whereby is visually indicated the particular character which is disposed in operative position.

In describing the invention in detail, reference is herein had to the accompanying 30 drawings in which—

Figure 1 is a side elevation of the invention;

Fig. 2 is an edge view of the same; and—

Fig. 3 is a broken detail section of the impact device.

Referring to said drawings, 1 indicates a circular disk having formed on its periphery at spaced intervals a series of characters 2, those herein shown being numerals. A 40 central pivot-pin 3 carried by said disk has its ends received in longitudinal slots 4 formed in opposite parallel yoke members 5 carried by or formed integral with a shank or head 6 which overlies a small portion of the periphery of the disk and extends radially outward from the latter.

Attached rigidly to, or formed integral with, said head 6 is a saddle plate 7 which extends in opposite directions a substantial 50 distance from said head. Said saddle plate is arcuately curved to correspond with the curvature of the circumferential edge, or periphery, of the disk and is adapted to seat closely upon said periphery. So seated, the 55 force of hammer blows delivered to the head will be evenly distributed over the entire

surface area of the disk contacted by said plate.

Provided in the periphery of the disk at suitably spaced intervals are sockets 8 in 60 which studs 9 carried by the saddle plate 7 are received when said plate is properly seated, said sockets being located so that when a desired character is disposed in alinement with the yoke, the studs 9 will 65 be interengaged with two thereof and the disk and the yoke will thereby be properly positioned and locked against relative movement.

One of the yoke members 5 has its end 70 prolonged and shaped to form a pointer or indicator 10 which is adapted to visually indicate the character which is disposed in operative position, there being provided on the adjacent side or face of the disk, as on 75 a dial, a series of characters 11 corresponding to those on the periphery of the disk, corresponding characters on the face and periphery being disposed in radial alinement.

To prevent mutilation of characters 2 which underlie the head 6 of the yoke when the tool is being operated, a socket 12 is 80 provided in the under side of said head, said socket being adapted to receive therein such underlying character.

When the tool is to be used for applying a certain character 2, the yoke is elevated to the limit permitted by the slots 4 engaged by the pivot pin 3, and the disk is then rotated to carry the corresponding character 11 into alinement with pointer 10, whereupon the yoke is lowered to properly seat the saddle plate 7. Then, holding the tool upright with the disk resting upon the article which is to receive the impression of 90 said certain character, one or more smart blows of a hammer are delivered to the head 6.

What is claimed is—

1. A multiple character stencil comprising a disk having a series of characters on its periphery, a centrally disposed pivot pin carried by said disk, a yoke disposed in straddling relation to said disk and having 105 slots in the parallel members thereof, said pin being received in said slots, an impact head formed on said yoke, and a saddle plate carried by said yoke and adapted to seat on the periphery of said disk.

2. A multiple character stencil comprising a disk having a series of characters on its

periphery, a yoke disposed in straddling relation to said disk and having an impact head, a pivotal connection between said yoke and said disk, and a saddle plate carried by 5 said yoke and adapted to seat on the periphery of said disk.

3. A multiple character stencil comprising a disk having a series of characters on its periphery, a yoke disposed in straddling relation to said disk and having an impact head, a pivotal connection between said yoke and said disk, a saddle plate carried by said 10 yoke and adapted to seat on the periphery of said disk, and means permitting radial outward movement of said yoke for unseating 15 said saddle plate.

4. A multiple character stencil comprising a disk having a series of characters on its periphery, a yoke disposed in straddling relation to said disk and having an impact head, a pivotal connection between said yoke and said disk, a saddle plate carried by said 20 yoke and adapted to seat on the periphery of said disk, and means permitting radial outward movement of said yoke for unseating 25 said saddle plate, and interlocking means preventing relative rotary movement of said disk and said yoke when said saddle is seated.

5. A multiple character stencil comprising a disk having a series of characters disposed in spaced relation on its periphery, a yoke disposed in straddling relation to said disk and having the parallel members thereof 30 pivotally connected to the axis of said disk, said connection permitting a limited range of radial movement of said yoke, an impact head formed on said yoke, and a saddle plate carried by said yoke and adapted for movement 35 with the latter into and out of seating relation to the periphery of said disk, said plate carrying means for interengagement with said disk whereby the latter is secured 40 against rotation.

6. A multiple character stencil comprising a disk having a series of characters disposed in spaced relation on its periphery, a yoke disposed in straddling relation to said disk and having the parallel members thereof 45 pivotally connected to the axis of said disk, said connection permitting a limited range 50

of radial movement of said yoke, an impact head formed on said yoke, and a saddle plate carried by said yoke and adapted for movement with the latter into and out of seating 55 relation to the periphery of said disk, said disk having sockets provided in its periphery, and said plate having studs for seating in said sockets.

7. A multiple character stencil comprising a disk having a series of characters disposed in spaced relation on its periphery, a yoke disposed in straddling relation to said disk and having the parallel members thereof 60 pivotally connected to the axis of said disk, said connection permitting a limited range of radial movement of said yoke, an impact head formed on said yoke, and a saddle plate carried by said yoke and adapted for movement 65 with the latter into and out of seating relation to the periphery of said disk, said disk having sockets provided in its periphery, and said plate having studs for seating in said sockets, said plate having a socket in 70 its under face for the reception of one of the 75 series of characters.

8. A multiple character stencil comprising a disk having a series of characters disposed in spaced relation on its periphery, a yoke disposed in straddling relation to said disk and having the parallel members thereof 80 pivotally connected to the axis of said disk, said connection permitting a limited range of radial movement of said yoke, a radially disposed impact head formed on the outer 85 end of said yoke, and a saddle plate carried by said yoke and adapted for movement into and out of seating relation to the periphery of said disk, a pointer formed on the end of one of the yoke members, and a series of 90 characters disposed on a side of said disk, said pointer and the last mentioned series being adapted to coöperate for visually indicating the character of the first series which occupies operative position. 95

In testimony whereof, I affix my signature in presence of two subscribing witnesses.

WILLIAM H. STRAUSER.
